Primary Examiner — T Chase Nelson(74) *Attorney, Agent, or Firm* — Sterne, Kessler, Goldstein & Fox P.L.L.C.**CLAIM**

The ornamental design for a shoe, as shown and described.

DESCRIPTION

FIG. 1 is a bottom perspective view of a shoe showing the claimed design;

FIG. 2 is a bottom view thereof;

FIG. 3 is a side view thereof;

FIG. 4 is another side view thereof;

FIG. 5 is a front view thereof;

FIG. 6 is a rear view;

FIG. 7 is a bottom perspective view of another embodiment of a shoe showing the claimed design;

FIG. 8 is a bottom view thereof;

FIG. 9 is a side view thereof;

FIG. 10 is another side view thereof;

FIG. 11 is a front view thereof; and,

FIG. 12 is a rear view.

The broken lines in the figures show portions of the shoe that form no part of the claimed design.
